AIR CONDITIONING APPARATUS
UTILIZING ICESamuel M. Anderson, Sharon, Mass., assignor to
B. F. Sturtevant Company, Inc., Boston, Mass.

Application February 26, 1935, Serial No. 8,293

4 Claims. (Cl. 62—131)

This invention relates to methods and apparatus for the cooling of air and relates more particularly to the cooling of air supplied to passengers in a railway passenger car.

5 The present invention is an improvement over that disclosed and claimed in my Patent No. 1,972,912, issued September 11, 1934.

According to this invention an ice bin comprising an insulated casing for the reception of ice cakes in bulk is mounted on the under side of a railway passenger car. An air cooling compartment is mounted in the roof zone of the car. Water cooled by the melting of ice in the bin, is circulated through the cooling compartment to cool the air passing therethrough. The water circulated to the cooling compartment is cooled by direct contact with the lower surface of the ice cakes at the bottom of the bin.

According to a feature of this invention the 20 ice bin is provided with a floor which slopes from each side of the car to the center thereof, whereby, as the ice at the bottom of the bin is melted, more ice slides down the inclined floor of the bin towards the center; the arrangement being such, that the ice always presents substantially a uniform surface of contact between water and ice, as long as there is any ice in the bin.

According to another feature of this invention, 25 an overflow pipe is located in the center of the bin to drain the excess water from the melted ice to the tracks. The overflow point is adjustable to compensate for the varying quantities of ice melted, due to different temperature conditions encountered in service.

According to another feature of the invention, the air conditioning chamber contains a pre-cooling coil through which a small portion of the water normally recirculated to the ice bin for 30 recooling, is continuously shunted from the main air cooling apparatus; the quantity of this shunted water being normally equal to the amount of excess water which is being continuously added to that in the ice bin, due to the melting of the ice therein. The water after passing through 35 the pre-cooling coil, passes to the overflow in the center of the bin and is drained as excess water to the tracks. With this arrangement the excess water, drained to the tracks is at a higher 40 temperature than the excess water which would normally be drained directly from the ice bin, due to its having absorbed additional heat in the pre-cooler coil. Thus the ice in the bin is 45 conserved to the maximum degree possible.

An object of the invention is to provide an

efficient, inexpensive apparatus for the conditioning of air.

Another object of the invention is to provide an air cooling system, utilizing ice, providing a uniform cooling effect.

Other objects of the invention will be apparent from the following descriptions taken together with the drawing.

The invention will now be described with reference to the drawing, of which:

Fig. 1 is a partial side view of a railway passenger car equipped with the present invention;

Fig. 2 is a sectional view along lines 2—2 of Fig. 1, and

Fig. 3 is a diagrammatic view, illustrating the 15 lay-out of the apparatus.

The ice bin, indicated generally by the numeral 5, is located on the under side and at about the longitudinal center of the car 6. The bin is provided with the two refrigerator type doors 7 20 for servicing with ice. As shown more clearly by Fig. 2, the ice bin 6, has the floors 8, which slope a substantial degree towards the center of the car, but at the center, are provided with a flattened portion 9.

Just above the flattened portion 9, of the floor and at substantially the lower-most point in the bin, is the pump intake pipe 11, into which the ice water, to be circulated to the cooling compartment, is drawn. The pipe 11 is so arranged with 30 respect to the overflow pipe which will be described later, that the pump suction will never be out of water on the steepest incline or grade, found in ordinary railway operation.

As shown more clearly by Figs. 2 and 3, at each 35 end of the bin 6, is a rectangular water distributing box 23, between which are formed a sump. Between each box and the bin proper is a strainer 24, which acts to remove objectionable particles of dirt which might be carried into the system by 40 the ice in the bin.

To one box 23, is connected the intake pipe 11, of the pump 12 and to the other box 23 is connected the return water pipe 16 from the cooling compartment 15. It is seen that the water passes 45 longitudinally through the bin in contact with the lower surface of the ice.

The water circulated in the system is cooled by contact with the lower-most ice cakes stored in the bin. As the ice melts in providing the desired cooling effect, the stored ice cakes slide down the inclined floor 8, to provide at all times, so long as any ice remains in the bin, a substantially uniform ice surface in contact with the 50 55

cooling water in the lowermost portion of the bin.

The ice water indrawn into the pump intake pipe 11, passes into the pump 12, and thence through pipe 13, to the main cooling coils 14, in the air cooling compartment 15. The water is recirculated then through pipe 16, back into the ice bin 6. It is preferred that two similar air cooling compartments 15 to be provided, one in each end of the car. Fig. 3 illustrates the piping for two such compartments.

A small portion of the cooling water leaving the main cooling coils 14, is shunted at the T connection 17, through the pre-cooler coil 18, and after passing through the pre-cooler coil, passes through the pipe 19, into the overflow pipe 20. As stated before, the amount of water shunted through the pre-cooling coil is as closely as can be determined, the amount the melting ice adds normally to that in the ice bin. Thus the pre-cooler extracts, so to speak, additional cold energy from the excess water so that it is drained to the tracks at a temperature several degrees higher than were it drained directly from the ice bin.

An overflow pipe 20, contains a plurality of openings 21, which are spaced the height thereof. The sleeve 22, slidably mounted on the pipe 20, is adapted to be moved up and down to cover the openings 21, thus adjusting the overflow level to be maintained in the ice bin. If preferred the openings 21, may be tapped and provided with plugs, the overflow, thereof then being adjusted by the removal of a plug from one of the different openings 21. This adjustment was provided to prevent the accumulation of too much water in the ice bin, as where, due to unusually hot weather, more water is provided by the melting ice than is exhausted by the pipe 19, in the overflow pipe 20.

The lowermost opening 21, is located above the intake pipe 11, so that the intake pipe is covered at all times.

Whereas one embodiment of the invention has been described for the purpose of illustration, it should be understood that the invention is not limited to the precise arrangement described, since many departures may occur to those skilled in the art, after having had access to this disclosure.

What is claimed is:

1. Air conditioning apparatus comprising a sump to contain ice, means for flowing water through and around the ice in said sump, an ice compartment surmounting the sump and containing ice unexposed to the water and arranged to feed ice to the sump as ice therein melts, an air cooling unit, cooling means in said unit for conditioning the air passing therethrough, means for circulating water from said sump to said cooling means, a precooler coil in said unit, means

for continuously shunting a portion of the water leaving said cooling means through said coil, an overflow pipe in said sump, means for returning the remainder of the water leaving said cooling means to said sump, and means for passing water from said precooler coil to the water adjacent said overflow pipe. 5

2. Air conditioning apparatus comprising a sump to contain ice, means for flowing water through and around the ice in said sump, an ice compartment surmounting the sump and containing ice unexposed to the water and arranged to feed ice to the sump as ice therein melts, an air cooling unit, cooling means in said unit for conditioning the air passing therethrough, means for circulating water from said sump to said cooling means, a precooler coil in said unit, means for continuously shunting a portion of the water from said cooling means through said coil, means for returning the remainder of the water leaving said cooling means to said sump, an overflow pipe in said sump, means for passing water returned from said precooler coil to the water adjacent said pipe, and means for adjusting the overflow point of said pipe. 20 25

3. Air conditioning apparatus comprising a sump to contain ice, an ice compartment surmounting the sump for storing ice unexposed to the water in said sump and arranged to feed ice to the sump as the ice therein melts, an air cooling unit, means for flowing water in contact with the surface of the ice in said sump and for supplying same to said unit, a precooler coil in said unit, means for continuously shunting a portion of the water returned from said cooling 35 unit through said coil, an overflow pipe, an overflow chamber around said pipe communicating with the water in said sump so as to have the same water level, means for returning the water returned from said coil to said chamber, and 40 means for returning the remaining portion of the water returned from said unit to said sump.

4. Air conditioning apparatus comprising a sump to contain ice, an ice compartment surmounting the sump for storing ice unexposed to 45 the water in said sump and arranged to feed ice to the sump as the ice therein melts, an air cooling unit, means for flowing water in contact with the surface of the ice in said sump and for supplying same to said unit, a precooler coil in said 50 unit, means for continuously shunting a portion of the water returned from said cooling unit through said coil, an overflow pipe, an overflow chamber around said pipe communicating with the water in said sump so as to have the same 55 water level, means for returning the water returned from said coil to said chamber, means for returning the remaining portion of the water returned from said unit to said sump, and means for adjusting the overflow point of said pipe. 60
